UNITED STATES PATENT OFFICE.

ROBERT H. SMILIE, OF OAKLAND, CALIFORNIA.

TENNIS RACKET.

Application filed December 17, 1927. Serial No. 240,722.

My invention relates to improvements in tennis rackets. The game of tennis is found to be a rather expensive game, for one reason due to the rapid wearing out of the strings 5 of the rackets used. On the close observation under a microscope of the playing surface of a racket I have discovered that invariably the strings break down at their intersections or crossings. This of course may be explained as caused by the frictional engagement between the strings for although a racket may be very tightly strung there is always a more or less lateral motion of each string with respect to the strings with which it is 10 interlaced. Each impact between the ball and the racket causes the strings of the intersections so brought into play, to be pressed together and so bruise and permanently injure their contacting surfaces. My observation also disclosed the fact that on an impact between a ball and racket, at most four 15 strings are actually brought into contact with the ball, and due to the fact that the coefficient of friction of string on string is insufficient of 20 to prevent the lateral motion of one string with respect to its intersecting string, the load placed on the racket by the impingement with the ball is carried largely by the four strings so brought into contact.

In general it is the object of my invention to provide an insulating means between the intersecting strings of a racket and thereby to prevent the frictional engagement of such intersecting strings and consequently to 25 prevent their bruising and wearing.

Another object of my invention is the provision of means whereby the load placed on a racket by its impingement with a ball, will be more or less evenly distributed on all of 30 its strings thereby eliminating any undue strains from being placed on any one string.

Another object of my invention is the provision of a flexible, double concaved disc to be interposed between intersecting strings 35 of a racket and in which the intersecting portions of said strings may be embedded and embraced thereby.

Another object of my invention is the provision of an insulating disc adapted to be interposed between the intersections of the strings of a racket, and which is made of a material, the coefficient of friction of which on the strings of a racket is greater than the coefficient of friction between string on 40 string, and which will therefore prevent the strings from creeping.

My invention possesses other advantageous features, some of which with the foregoing will be set forth at length in the following description where I shall outline in full that 45 form of the tennis racket of my invention which I have selected for illustration in the drawings accompanying and forming part of the present specification. Although I have shown in the drawings but one form of 50 my invention, I do not desire to be limited thereto, since the invention as defined in the claims may be embodied in other forms also.

Referring to the drawings:

Fig. 1 is an elevational view of a tennis 55 racket embodying the use of my invention.

Fig. 2 is a plan view of my flexible, double concaved insulating disc.

Fig. 3 is a mid-section of the insulating disc shown in Fig. 2.

Fig. 4 is a sectional view taken parallel to one set of intersecting strings of a racket showing the manner in which my insulating discs are interposed between the intersections of a string.

Fig. 5 is a mid-sectional view of a reinforced insulating disc.

Fig. 6 is a perspective view of a string intersection showing the manner in which such intersecting strings are embedded and embraced in an interposed insulating disc.

In accordance with my invention my insulating disc 1 is preferably molded of rubber or other flexible material. Each face of my insulating disc is dished or concave as 60 at 2 and 3. In actual practice I have made these discs of a diameter approximately equal to three diameters of the strings on a racket but they may of course be made of any other suitable size. These insulating discs are then interposed between intersections of the strings of a racket and when so 65 interposed are found to assume the formation as best shown in Figs. 4 and 6. Refer-

ring particularly to Fig. 6, the string 4 of a pair of intersecting strings 4 and 5 is embedded within the upper surface of one of my insulating discs while the string 5 is embedded in its lower surface. It will be noted that the string 4 engages with the peripheral portions 6 and 7 to cause these peripheral portions to embrace the string 5 and that the string 5 engages the peripheral portions 8 and 9 so as to cause these peripheral portions to embrace string 4. The material of which these insulating discs are made is so chosen 70 that its coefficient of the friction on the

strings is substantially greater than the coefficient of friction between a string on a string. By having such an increased coefficient of friction and due to the manner in 5 which the intersecting strings are embedded and embraced within the insulating discs the strings are prevented from creeping or moving laterally on each other thereby decreasing the frictional wear of the strings.

10 It has been found that the resiliency of a racket constructed in accordance with my invention is greatly increased thereby producing a faster racket. To further increase the resiliency of the racket and to increase 15 the durability of my insulating discs I have found it preferable to reenforce the insulating disc by means of a centrally disposed fibrous disc 11 as shown in Fig. 5. This fiber reenforcing member is embedded in and 20 made integral with the insulating disc. In this form of insulating disc it is to be noted that at its center its thickness is substantially that of the fiber reenforcing member. When 25 such an insulating disc is interposed between intersecting strings, the fiber 11 is practically all that separates the strings and being harder and more resilient than its surrounding rubber, responds somewhat faster to the action of the strings than an unreenforced disc.

30 The fiber reenforcing member also increases the durability and life of the insulating disc, their life being about equal to the life of the strings.

The use of such insulating discs also has 35 the effect of producing a greater and more even frictional surface between the racket and the ball thereby permitting a greater accuracy when it is desired to give a predetermined spin to the ball.

40 Although I have found it preferable to construct such an insulating disc of a flexible material, I have constructed some of aluminum. When so made they are molded to the form show in Fig. 6 and are provided with 45 wedge shaped grooves for gripping the strings. These metallic devices serve to insulate or separate the intersecting strings but it has been found that their gripping action on the strings is not as great as that 50 of the rubber insulation.

By preventing the lateral motion or creep-

ing of the strings with respect to each other it can be seen that when there is an impingement between a ball and the racket the load thereby placed on the racket, will be carried not only by the four strings with which the ball actually engages, but will be distributed to a plurality of strings adjacent these four strings. This of course decreases the chances of a worn or defective string from breaking due to carrying too great a portion of the total load and also insures a uniform playing surface at all times.

By the above disclosure it can be seen that I have not only provided a means whereby the life of the strings of a tennis racket is greatly increased but by the use of such means the playing qualities of a racket are also improved, that is, the racket is faster and enables the player to control more accurately the motion of the ball. Actually the life of the strings has been found to be doubled or tripled and that for a given amount of energy, the rebound of a ball when my improved racket is used, is much greater 75 than with the rackets now in use.

I claim:

1. A racket comprising a frame, a plurality of interlaced strings supported by said frame and a plurality of deformed double concave discs interposed between said strings. 80

2. As a new article of manufacture a disc of flexible material provided with a central reinforcing member and adapted to insulate the strings of a reticulated material. 85

3. As a new article of manufacture, a flexible double concave disc adapted to insulate the strings of a racket.

4. A tennis racket comprising a frame, a plurality of intersecting strings supported 90 by said frame and a plurality of flexible centrally reinforced discs interposed between said strings.

5. A tennis racket comprising a frame, a plurality of intersecting strings supported 95 by said frame and a plurality of flexible, double concave discs interposed between said strings.

In testimony whereof, I have hereunto set my hand.

ROBERT H. SMILIE.
